UNITED STATES PATENT OFFICE

2,546,668

SIDE-WALL CORING DEVICE

John H. Kirby, II, Houston, Tex.

Substituted for application Serial No. 405,915,
August 8, 1941. This application November 23,
1945, Serial No. 630,199½

2 Claims. (Cl. 255—1.4)

1

This invention relates to new and useful improvements in side wall sampling devices.

This application constitutes a substitution or refile of my prior abandoned application, Serial No. 405,915, filed August 8, 1941. This application is also a companion application to my applications, Serial No. 667,798, and Serial No. 714,324.

An important object of the invention is to provide a new and improved sampling device wherein samples of the formation are taken.

Another object of the invention is to provide an improved sampling device wherein a full length and intact sample may be obtained.

A still further object of the invention is to provide an improved side wall sampling device which is moved towards the formation that is desired to be tested so that a core the length of the sample tube may be obtained.

A further object of the invention is to provide an improved sampling device wherein the outward progress of the sampling tube is greatly retarded so as to produce a better sample.

Still another object of the invention is to provide an improved sampling device wherein the device runs in a bath of lubricant and the pressure surrounding said device acts upon said lubricant so that the pressure within and without the device is equalized.

Another object of the invention is to provide an improved sampling device wherein the sampling-receiving tube is rotated when it is being forced out through the substance of which a sample is desired, but is not rotated when it is withdrawn therefrom, thereby reducing the possibility of breaking the sampling tube or damaging it in some manner.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a vertical cross-sectional view of the upper portion of a device constructed in accordance with the invention;

Fig. 2 is a similar view of the lower portion of the device and constitutes a spaced continuation of the portion shown in Fig. 1;

Fig. 3 is a horizontal cross-sectional view taken on the line 3—3 of Figure 1;

Fig. 4 is a horizontal cross-sectional view taken on the line 4—4 of Fig. 1;

2

Fig. 5 is a horizontal cross-sectional view taken on the line 5—5 of Fig. 2;

Fig. 6 is a horizontal cross-sectional view taken on the line 6—6 of Fig. 2;

5 Fig. 7 is an enlarged view, partly in section and partly in elevation of the hydraulic pump used in the device shown in Figs. 1 and 2;

Fig. 8 is an enlarged isometric view of one of the abutting plates used in the device shown in Figs. 1 and 2;

10 Fig. 9 is an enlarged view, partly in section, showing the sample tube used in the device shown in Figs. 1 and 2;

Fig. 10 is a vertical cross-sectional view taken 15 on the line 10—10 in Fig. 9;

Fig. 11 is a vertical cross-sectional view taken on the line 11—11 of Fig. 9;

Fig. 12 is an enlarged side elevational view of the sampling tool;

20 Fig. 13 is a vertical cross-sectional view taken on the line 13—13 of Fig. 12; and

Fig. 14 is an enlarged isometrical view of the driving gear for the sampling tube.

In the drawings, the numeral 10 designates a 25 side wall sampling device which includes the hollow cylindrical housing 11 which carries the sampling assembly. The upper and lower ends of the housing 11 are internally screw-threaded at 12 and externally threaded at 13 to engage complementary threads on the head 83 and the shoe or plug 79 respectively to form an enclosure for the sampling assembly 14 which fits therein and to which further detailed reference will be made.

35 A pair of tubular upright supporting members 15 in end to end relation snugly engage the inner surface of the housing 11 and support the lower assembly. A hanger bar 16 is connected to the upper end of the lowermost support, and is used for the purpose of pulling the supports out of the housing 11.

40 The support below the hanger 16 is provided proximate its upper and lower ends with openings 17 in alignment with the openings 18 in the side wall of the housing 11.

45 The housing 11 about the openings 18 is tapered outwardly at 19. Ram heads 20 fit within recesses formed in the thickened portions and thereby form continuous surfaces when said heads are lying against the housing 11. Connected to the underside of the heads 20 are rods 21 which pass through the respective openings 17 and 18 to the interior of said housing. Connected to the innermost end of said rods are pistons 22 (see Fig. 2) which work within cylinders 23.

55 Packing glands 24 lie within the openings

17 and 18, and pack off around the rods 21 so as to prevent leakage of fluid along the surface of the rods.

Each of the cylinders 23 is provided with a pair of openings (not shown) which establish communication between the interior of said cylinder to pipes 25 and 26. As may be seen in Figure 2, the pistons 22 at all times lie between said openings so that fluid flowing from the pipe 25 into the cylinders will force the pistons towards the other opening, thereby moving the rams 20 outwardly; and fluid within the cylinder, in front of the pistons, will flow out through the pipe 26 as will be hereinafter further discussed. Obviously, as the process is reversed and fluid flows from the pipe 26 into the cylinders 23, it will move the pistons towards the other opening and force the fluid that has entered said cylinder back out through the pipe 25. The cylinders 23 are suitably supported on the lower support 15.

In order to force the fluid through the pipes 25 and 26, there is provided a pump 30' that is clearly shown in Fig. 7. This pump has a driving shaft 27 upon which is mounted a sprocket wheel 28, and said sprocket wheel is placed off-center within the housing 29 of said pump so that it engages only a portion of the annular gear element 30. As the sprocket 28 is rotated, say in a clockwise direction, it will pick up fluid from the port 32 and discharge it through the port 31; and when the sprocket is reversed and rotated in an anti-clockwise direction, it will pick up fluid from the port 31 and force it out through the port 32. The pump 30' is likewise suitably supported on the lower support 15 and hence forms an integral part of the assembly 14.

The ports 31 and 32 of the pump 30' are connected to identical inlet and outlet check valves, of which the identical description of one is deemed sufficient. The port 32 of the pump is connected by means of a pipe (not shown) to the valve 33, which will allow fluid to enter said valve from within the housing 11, it being understood that the housing is maintained full, or substantially full, of a suitable fluid and means is provided to maintain equalized pressure between the interior and the exterior of the housing as will more fully appear.

Mounted above the inlet valve 33 is an outlet valve 34, which has been shown in cross-section. Fluid from the valve 33 may flow up and strike the ball 35, compressing the spring 36, and flow out through the port 37. However, when fluid attempts to flow through the port 37 to the interior of said valve, the ball valve 35 will seat, as shown in the drawings, and thereby check the fluid from flowing therethrough. The port 31 has an inlet valve 38, identical to the inlet valve 33, and an outlet valve 39, identical to the outlet valve 34.

The valves 38 and 39 are connected into the pipe 26 by a pipe 40, while the valves 33 and 34 are connected into the pipe 25 by means of a pipe 41. Thus, as may be seen, by rotating the pump 30' so that fluid will flow through the pipe 41 into the pipe 25, it will force the rams 20 outwardly while the fluid from in front of the piston will flow through the pipe 26, up through the pipe 40, and out through the valve 39. Also, when the pump is reversed and fluid is forced out through the port 31, and thence through the pipes 40 and 26, it will enter in front of the pistons and move said pistons back towards the pipe 25, thereby moving the rams inwardly. Fluid from this portion of the cylinder will flow out

through the pipe 25, up through the pipe 41, and out through the outlet valve 34. It is pointed out that the pistons 22 are surrounded by suitable piston rings 22'.

A prime mover shown as an electric motor 43 is suitably mounted within the housing 11 intermediate the pump 30' and the lower cylinder 23 and has an upwardly directed drive shaft 44 which is connected to the shaft 27 of the pump 10 by means of a universal joint 45. Obviously, this motor will actuate said pump. Extending from the lower portion of the motor 43 is a drive shaft 46 which has a gear (not shown) mounted thereon, and said gear engages a pinion 47 fixed upon the shaft 48. Adjacent the pinion 47 and fixed upon the shaft 48 is a driving gear 49.

The driving gear 49 engages a driven gear 50 which in turn engages an elongated pinion 51 so that all are rotated together. A gear 52 is 20 mounted on one end of the pinion 51, and is locked thereon so as to be rotated with said pinion. The outermost ends of the pinion 51 are suitably mounted in the support 15 by bearings 53. Meshing with the gear 52 is an enlarged gear head 54 of a threaded guide 55, and the outermost ends of said guide are suitably mounted in the support 15 on bearings 56.

An idler gear 57 engages the gear head 54, and meshing with the idler 57 is an enlarged gear head 58 of a second threaded guide 59. The outermost ends of said guide are suitably mounted within the support 15 by means of bearings 60. Thus, as the pinion 51 is rotated, it will rotate the gear train 54, 57 and 58.

A driving gear 61 is confined on the guide 55, and the inner surface of said gear is screw-threaded so as to engage with the screw-threaded surface of said guide, and as the same is rotated it will be moved along said guide due to the screw-threaded engagement. The teeth of said gear engage the pinion 51 so that as the pinion is rotated, it will rotate the gear 61 and move it along the guide 55. A similar gear 62 is mounted on the guide 59.

An intermediate gear 63 meshes with the gears 61 and 62, whereby the pinion 51 rotates both the gears 61 and 62. A housing 64 encloses said gears and carries the innermost end of a sampling tube 65. All of these gears are suitably mounted on ball bearings 66, and the intermediate gear 63 has an axial opening therethrough. A pin 67 connects the innermost end of the sampler 65 to the gear 63. The outer circumference of the innermost end of said tube is provided with a plurality of flared openings 68, as may best be seen in Figures 11-13.

A flange 69 is securely mounted on the shank of the gear 63. This flange overlies the innermost end of said sampler 65 and is provided with a plurality of angular openings 70 (Figure 11), the outermost end of which is internally screw-threaded. Balls 71 lie within said openings and engage within the flared opening 68 of the sampler 65. Springs 72 act to urge said balls towards said sampler at all times and are retained in said openings by retainer caps 73. Thus, as the flange 69 is rotated in a clockwise direction as viewed from its outer end, the balls 71 lock the sampler in relation to said flange, but when said flange is rotated in an anti-clockwise direction, said balls will snap up against the tension of the spring, allowing the sampler to remain still. Hence, while the sampler is moving outwardly, it 75 will rotate, but when it is being retrieved, by re-

verse rotation of the guides 55 and 59, it will not be rotated.

The housing 11 is provided with an enlarged opening 14 through which the sampler 65 passes. A packing gland 75 engages within said opening and surrounds said sampler so as to prevent leakage of fluid axially thereof. On the lowermost end of the housing 64, there is a depending trigger 76. Mounted below the lowermost guide 59 on the support 15 are a pair of switches 77 and 78. The switch 77 is the initial starting switch which starts the sampler in its outward travel. When the trigger 76 flips the switch 78, it will reverse the motor 43, thereby reversing all of the gears so as to retract said sampler, as will herein-after further be discussed.

The shoe 79 is mounted on the lowermost end of the housing 11, and is provided in its lower end with a plurality of openings 80. The shoe has an elongated recess 81 in its central portion which communicates with the openings 80. A flexible diaphragm 82 lies within the recess 81 and is securely attached to the upper portion of said shoe so that fluid acting on the outer surface of the shoe may enter the ports 80 and depress the diaphragm 82 so as to equalize the pressure on the interior and exterior of the device.

The head 83 mounted on the uppermost end of the housing 11 has a depending flange 84 which carries the electrical contacts 85 from which wires extend by way of the conduit 92 to the motor 43 and to the switches 77 and 78.

The head 83 is also provided with an opening 88 which extends therethrough and is closed by a plug 89. A central recess 86 is provided on the top side of said head, and is internally screw-threaded so as to receive a fishing neck 87 which has an axial bore throughout its length. Its uppermost end receives a running cable 90 which is securely attached thereto in the usual manner. The cable is what is commonly known as an "electrical cable"; that is, it has supporting qualities and is also capable of conducting electricity. It may have separate electrical conductors woven therein as is shown in the drawings. These conductors are connected to the electrical connections 85 whereby electrical current may flow from the surface of the ground down to the device so as to operate the motor and the switches.

The head 83, around its central opening, receives a packing gland 91. Thus, as may be seen, the device is fluid tight.

In actual operation, the cap 89 of the head 83 is removed and, as already indicated, the entire interior of said tool is filled with a suitable lubricant. The cap is then replaced so that the tool works in oil or some other suitable fluid. The device is run into the well bore on the cable 90 in the conventional manner. When the desired location has been reached, the motor 43 is started so as to rotate the shaft 44 and operate the pump 30 so as to force fluid out through the port 32 and the pipe 25. The entire tool being full of oil, the pump will draw the oil in through the inlet valve 33 and force it out into the pipe 25, whence it is forced into the cylinders 23 of the rams 20 and 42 and so that they will move outwardly and engage the surface of the bore.

It is pointed out that this device could be run down through the casing and the rams would abut the interior of said casing. While this is taking place, the shaft 46 through the medium of the gear (not shown) is rotating the drive gear 47 which, in turn, rotates the gears 49 and

50, and the pinion 51. The pinion 51 will be rotated in a clockwise direction, the gear 61 will be rotated in an anti-clockwise direction; while the gear 63 and the sampler 65 will be rotated in a clockwise direction, and the gear 62 will be rotated in an anti-clockwise direction the same as the gear 61. Thus, as said gears are rotated, they will feed the sampler outwardly due to the threaded guides 55 and 59. However, the gear 52 of the pinion 51 is attempting to rotate the guide member 55 in a counter-clockwise direction, but the gear ratio between the pinion 51 and the gear 61 is slightly greater than the gear ratio between the gear 52 and the gear head 54. Thus, the sampler 65 is slowly advanced in a direction along its axis and is, at the same time, rotated about its axis so that a sample is cut and enters the sampler.

When the sampler carrier 64 has reached its outermost position, the trigger 76 flips the switch 78, thereby reversing the motor 43, which will reverse the gear pump and begin drawing oil in the intake valve 33 so as to pump the same into the pipe 26 and move the piston 22 back to its original position, thereby bringing in the rams 20 and 42. The pinion 51 will be rotated in a counter-clockwise direction while the gears 61 and 62 will be rotated in a clockwise direction so as to pull the sampler carrier back to its original position. The gear 63 will also be rotated in a counter-clockwise direction, the same as the pinion 51. Therefore, the flange 69, which is attached to the gear 63, will be rotated in a counter-clockwise direction which will allow the balls 71 to snap past the flared opening 68 of the sampler, thereby allowing the sampler to stand still and not rotate, and eliminating any danger which may be caused by this withdrawal if said sampler were rotated.

When the sampler 65 is completely withdrawn, the device is then ready to be withdrawn from the well, the trigger 76 having engaged the switch 77 so as to turn the motor 43 off. It is pointed out that, when the tool is placed in the well, there is a certain amount of fluid pressure within said well. It may be hydrostatic pressure or it may be gas or other fluid pressure from penetrated formations. Such pressure acts upon the diaphragm 82 located in the shoe 79, putting a pressure on the fluid within the device and thereby equalizing the pressure within said device with that on the outside thereof which, obviously, reduces the possibility of fluid leaking into or from the device.

What is claimed is:

1. A side wall sampling device including, an elongated housing adapted to be lowered in a well bore, an elongated support slidably fitting within the housing, threaded guide means mounted transversely of said support, gear means mounted on said guide means, a cutting tool adapted to be driven by said gear means and extensible sidewardly through an opening in the sidewall of the housing, a pump carried by said support, a pair of ram heads on the exterior of the housing opposite said cutting tool and adapted to be projected outwardly by said pump, driving means carried by said support and connected to drive said gear means and said pump, and power means supplied to said driving means to project said ram heads sidewardly to engage the side wall of the well bore to move the housing into engagement with the well bore wall at the opening for the cutting tool, and to rotate, advance, and retract said tool.

2. A side wall sampling device comprising, an elongated housing adapted to be lowered in a well bore, a pair of ram heads on the exterior of the housing in axially spaced relation, piston rods attached to said ram heads and sealably passing through the wall of the housing, a piston and cylinder assembly operatively connected to each of said rods, a hydraulic pump within the housing, a body of liquid within the housing adapted to be pumped by said pump to said cylinders to advance and retract the pistons and ram heads, closures at opposite ends of the housing to retain the liquid within the housing, the lowermost of said closures having an elongated recess therein and openings therethrough, a flexible diaphragm fitting within said recess and sealably secured to the closure at its inner end, whereby pressures interiorly and exteriorly of the housing are equalized and volumetric changes are compensated, threaded guide means mounted transversely of said housing, gear means mounted on said guide means, a cutting tool adapted to be driven by said gear means and extensible side-

wardly of said housing opposite said rams, driving means within said housing and connected to drive said gear means and said pump, and power means supplied to said driving means to drive said pump and cutting tool respectively to advance and retract the ram heads and to rotate, advance, and retract said cutting tool while the rams are in advanced position.
